BY

Geo. B. Wilcox, ATTORNEY

UNITED STATES PATENT OFFICE.

MORTIMER E. COOLEY, OF ANN ARBOR, MICHIGAN.

VACUUM-WRINGER.

SPECIFICATION forming part of Letters Patent No. 761,878, dated June 7, 1904.

Application filed May 11, 1903. Serial No. 156,713. (No model.)

To all whom it may concern:

Be it known that I, MORTIMER E. COOLEY, a citizen of the United States, residing at Ann Arbor, in the county of Washtenaw and State of Michigan, have invented certain new and useful Improvements in Vacuum-Wringers; and I do hereby declare the following to be a full, clear, and exact description of the invention, such as will enable others skilled in the art to which it appertains to make and use the same.

This is a machine for drying peat or other material by spreading it in a thin layer, passing the layer through the machine, and subjecting it during its passage to the combined action of pressure and suction. The material is carried on a belt part way around a revolving perforated cylinder in which is maintained a partial vacuum, and the pressure is applied to the back face of the belt while the material is in contact with the cylinder.

In the accompanying drawings, illustrating the machine, Figure 1 is a vertical cross-section of the machine. Fig. 2 is a front elevation, broken away in part, and Fig. 3 is a rear elevation, broken away in part, showing the machine with the belt removed.

The construction and operation of the machine are as follows.

The material to be dried is placed on the endless belt 1, moving in the direction indicated by arrows in Fig. 1, and is guided into the space 3 between the belt 1 and the cylinder 4, which travels with the belt and at the same speed. A constant pressure upon the material is maintained between the belt 1 and the cylinder 4 by means of rollers 5 on the back face of the belt. The rollers revolve in boxes 5^a, slidably mounted in slots 6^a in the main frames 6 of the machine, and each is yieldingly held against the belt by a spring 5^b, confined between the end of the slot 6^a and the box 5^a. The tension of the springs is adjustable by means of set-screws 5^c.

The peat or other material to be dried is pressed into a thin layer between the belt and the cylinder, and the water is squeezed out of it by the yielding pressure of the rollers 5. The water thus forced to the surface of the layer is drawn into the cylinder 4 through the

perforations 4^a by the vacuum maintained in the cylinder.

I prefer to employ the following means for maintaining the vacuum in the cylinder. The cylinder has solid heads 4^b mounted on the shaft 4^c, which turns in bearings in the main frames 6, and these heads have each a projecting circular flange 4^d. That part of the circumference of the cylinder not in contact with the peat is surrounded by a cylindrical casing 7, slightly larger in diameter than the cylinder 4. The casing has inwardly-turned longitudinal flanges 7^a and 7^b along its top and bottom edges and inwardly-turned circumferential flanges 7^c at each end. Air-tight joints are made between the flanges 7^a and 7^b and the walls of the cylinder by any convenient form of packing 8, and the opening 9, Fig. 2, between the flange 4^d of the cylinder-head 4^b and the flange 7^c of the casing is also made air-tight by yielding packing 10.

The casing 7 has openings 7^d, by which connection is made with any suitable means for exhausting air from the casing. Under the action of the partial vacuum in the casing the moisture and free air from the layer of peat is drawn through the perforations 4^a into the cylinder and thence out the opposite side of the cylinder into the chamber 12 between the casing and the cylinder, being finally drawn out of the casing through the openings 7^d.

The stationary casing 7 is supported by grooved wheels 13, which roll on the flange 4^d of the cylinder-head as the latter revolves. By this means the proper relative positions of the casing and the revolving cylinder are maintained, and the weight due to atmospheric pressure on the casing is transmitted through the wheels 13 and flanges 4^d, thereby minimizing resistance to rotation of the cylinder. The wheels 13 are mounted on shafts 13^a, turning in bearings 13^b on the casing.

The belt 1 may be mounted on any suitable system of rollers, and it may be of any desired length.

I have not illustrated the means for securing uniform speed between the belt and roller, as any suitable means, as gears or belts, may be employed for the purpose.

By the means above described I have pro-

duced a machine into which green peat or other material may be continuously fed and from which it is discharged in a partially-dry condition, the drying being effected by the 5 combined action of pressure and suction.

What I claim as my invention, and desire to secure by Letters Patent, is as follows:

1. A machine for drying peat or other material comprising a revoluble hollow cylinder 10 having circumferential perforations; a belt traveling in proximity to and around part of the circumference of said cylinder; and means for producing a partial vacuum within the cylinder, said means comprising an air-tight 15 casing extending around that part of the circumference of the cylinder not in contact with the material to be dried.
2. In a drier of the class described, a revoluble hollow perforated cylinder; means for 20 pressing material to be dried against one part of said revoluble cylinder, and an air-tight casing extending around that part of the cylinder not in contact with the material to be dried.
3. A machine for drying peat or other materials comprising a revoluble hollow cylinder with circumferential perforations; an endless belt traveling part way around and in 25 proximity to the cylinder; means for pressing the material between the belt and the cylinder, said means comprising rollers yieldingly held against the back face of the belt; and means for producing a partial vacuum within the cylinder, said means comprising a 30 case extending around that part of the circumference of the cylinder not in contact with the material to be dried; air-tight joints between the edges of the casing and the cylinder; said casing having openings for removing water and air.
4. A peat-drying machine comprising in 35 combination a revoluble hollow cylinder with perforated circumferential wall; an endless

belt traveling part way around the circumference of the cylinder in proximity thereto; 45 means for maintaining partial vacuum within the cylinder, said means comprising a stationary casing extending around that part of the circumference of the cylinder not in contact with the material to be dried; air-tight joints 50 between the edges of the casing and the cylinder; means for supporting the casing upon the revolving cylinder; said casing having openings for removal of air.

5. In a machine for drying peat, by passing it in a thin layer part way around a cylinder having circumferential perforations; means for maintaining a partial vacuum within the cylinder, said means comprising a stationary casing extending around that part of 60 the cylinder not in contact with the material to be dried; air-tight packings between the longitudinal edges of the casing and the circumference of the cylinder; outward circumferential flanges on the ends of the cylinder; 65 packings to maintain air-tight joints between the ends of the casing and said flanges; and means for supporting the casing upon the revolving cylinder, comprising wheels revolubly mounted upon the casing, said wheels being 70 adapted to roll on the circumferential flanges of the cylinder ends.

6. In a drier of the class described having a stationary casing partly inclosing a revolving cylinder; means for supporting the casing on 75 the cylinder comprising outwardly-extending circumferential flanges at the ends of the cylinder and wheels revolubly mounted upon the casing; said wheels being adapted to roll on the circumferential flanges of the cylinder. 80

In testimony whereof I affix my signature in presence of two witnesses.

MORTIMER E. COOLEY.
